COLLAPSIBLE MERRY-GO-ROUND

Harry Woeckner, also known as Harry Weckner,
Akron, Ohio, assignor of one-half to Chris
Miletti, Akron, and one-half to Peter Locke, Jr.,
New Milford, Ohio

Application July 12, 1950, Serial No. 173,358

3 Claims. (Cl. 272—33)

1

This invention relates to a merry-go-round ride for children.

The ride includes a plurality of frame members rotatably mounted on an upright member supported on a base. The base is designed to rest flat against a floor or a lawn or the like. Seats in which the children ride are provided in the frame members. Preferably there are two frame members which are identical to each other in size and shape and extend radially outward on opposite sides of the upright. If more than two members are employed they preferably are spaced apart at equal angles around the upright so that the weight of the riders is substantially balanced when the frames are rotated.

The frames may be rotated by a propelling device which, for example, includes a lever handle that is pivotally mounted on one of the frames and is connected to means adapted to frictionally engage the upright when pull is applied to the handle by one of the riders. As the handle is pulled in one direction, the engaging means frictionally engages the upright and the reaction force on the frames due to the pull on the handle causes the frames to rotate around the upright. The frames rotate in a direction opposite to the direction in which the lever is pulled. Rotating force is transmitted to the frame only when the handle is moved in one direction. After each power stroke the handle is swung back to its original position and this resets the engaging means so that another power stroke can be made. With several strokes of the lever the frames acquire sufficient momentum to continue to rotate on the base for a considerable length of time.

A feature of the ride is in the fact that the frames are designed to be swung toward the upright when the ride is not in use so that the ride may be folded into a compact bundle which is easily carried in a car or the like. The ride may also be shipped more conveniently in its folded position. For this purpose, one portion of each frame is pivotally connected to a collar rotatable about an upper end of the upright and another portion of each frame is pivotally connected to a collar rotatable about the lower end of the upright. As the frames are swung toward the upright one of these collars is adapted to slide along the upright toward the other collar until the frames are completely collapsed and the ride occupies very little space. In the preferred design the collar supporting the lower portions of the frames is adapted to slide upwardly toward the top of the upright when the frames

2

are folded. Legs which extend from the base to support the upright are detachably connected to the base so that they may be removed after the frames are folded against the upright.

The invention will be further described with reference to the drawings, in which—

Fig. 1 is a side elevation of the ride with the frame members in their unfolded position;

Figs. 2 and 3 are plan views of certain portions 10 of the structure taken on the lines 2—2 and 3—3, respectively, of Fig. 1;

Fig. 4 is a plan view of the ride with the frame members unfolded;

Fig. 5 is an enlarged detailed view of a portion 15 of the propelling device taken on line 5—5 of Fig. 4, shown partially in cross section;

Fig. 6 is a side elevation of the lever which operates the propelling device, taken on the line 6—6 of Fig. 1; and

Fig. 7 is a side elevation of the ride showing 20 the frame members in their folded position.

The base which supports the ride is formed with a flat plate 1 having a cylindrical block 2 welded at the center of the plate. The lower end 25 of a straight rod 4 of circular cross section is fastened securely in the block 2 by a setscrew 5. A tube 7, somewhat shorter than the length of one of the sides of plate 1, is welded along each side of the plate. These tubes 7 are preferably located so that one end of each tube is adjacent 30 a different corner of the plate in the manner shown in Fig. 2. The tubes 7 each serve as a socket to slidably receive the inner end of a leg 8. Each of these legs is a tubular member having its outer end 9 flattened. When the legs are located properly in their respective tubes 7 they extend horizontally outward from the base plate 1 in a swastika pattern, as shown in Fig. 2. These legs 8 are adapted to rest on a floor, lawn 35 or the like and provide a very stable support for the upright 4.

Extending symmetrically outward from the upright at 180° apart are the tubular frames 12, each of which is relatively heavy to withstand 45 compression, and thus is adapted to support a rider. The frames 12 are of identical shape and preferably each frame 12 is formed with one continuous tube. Each frame 12 is bent into a rectangular shape to form a straight, horizontal outer portion 13 and sides 14 which extend toward the upright 4. Near the upright 4 the sides 14 are bent inwardly toward the upright. The innermost end 15 of each tube is flattened, and these ends are pivotally fastened by the cap 50 screws 16 to the opposite sides of a collar 17

which loosely surrounds the upright 4. The collar rotates around the upright when the ride is in use, and it slides freely up and down on the upright so that the frame members may be folded toward one another. The bottom of collar 17 rests on a thin bearing 18 which in turn rests on the top of the block 2. As shown in Fig. 1 the inwardly bent portions of the sides 14 of each frame adjacent the upright 4 are horizontal. The sides 14 are also bent at 20 so that the frame slopes upwardly at about thirty degrees. Braces 21 hold the inner ends of the sides in position.

Each frame 12 is supported near its outer end by a horizontal light tension brace 23 which is preferably a flat bar. The inner end of each of the braces 23 is pivotally fastened by a bolt 24 to an ear 25 which projects toward the frame from the side of a collar 26 which surrounds the upright 4 near its upper end. This collar 26 fits loosely around the upright and is freely pivotal around the upright. It is supported on a stop 28 which is preferably a pin which extends diametrically through the upright 4.

As shown in Fig. 4 each brace 23 is bent outwardly from the ear 25 to which it is attached and then each is bent at 29 so that it extends toward the outer portion 13 of its respective frame 12. The outer end 30 of each brace 23 is pivotally fastened to the side 14 adjacent it by a rivet 33.

Spaced inwardly from the end 13 of each frame 12 is a cross brace 35 extending between the sides 14 which supports the fabric 36 which forms a seat in which a child rides. The fabric 36 is preferably a heavy duck material and it is looped around the brace 35 and the end 13 of the member. The fabric drapes loosely between the end 13 and the brace 35 to form a suitable seat. Another cross brace 37 is provided below the seat which serves as a foot rest for the rider.

The ride may be collapsed to the position shown in Fig. 7 by merely swinging the frames 12 upwardly toward one another in the direction of the arrows shown in Fig. 1. The frames 12 are pivoted around the screws 16 and the braces 23 are pivoted around the bolts 24. In the preferred design, as the braces 23 are swung upwardly they lift the frames 12 and the collar 16 slides upward on the upright 4 toward the upper collar 26. The upper collar 26 remains in a substantially fixed position. The legs 8 may be slid out of their respective tubes 7 after the frame members 12 are folded.

The frames are rotated by the lever or handle 39 which operates the engaging unit 40 mounted at the top of the upright 4.

The unit 40 closely resembles a band brake. A plan view is shown in Fig. 4, and Fig. 5 is an enlarged detail. It includes a cylindrical collar 42 which is fastened rigidly around the upright 4. The clevis 43 is provided with relatively wide sides and is of a thin gauge material. The sides of the clevis fit across the upper and lower surface of the collar 42 and each side loosely surrounds the upright 4 so that the clevis can be rotated on the collar 42 around the upright. The outer ends 44 of the legs of the clevis project a short distance beyond the cylindrical surface of the collar 42 and these legs are sandwiched between the legs of a somewhat smaller clevis 45. The clevis 45 is pivotally engaged with the ends 44 of the legs 43 by a vertical bolt 47. One end 50 of a flexible steel band 51 is looped around bolt 47 and fastened securely thereto between the legs of clevis 43. This band

is somewhat narrower than the thickness of the collar 42 and fits through the space between the cylindrical surface of collar 42 and the back of the clevis 43. It extends around the cylindrical surface of the collar 42 and its opposite end 53 is looped around and securely fastened to a vertical bolt 55 which extends between the legs of the clevis 45 near to the back of this clevis.

In order to maintain a certain amount of tension in the steel band 51 at all times a coil spring 56 is stretched between the back of clevis 43 and the outer end of a bar 57 which is fastened to the middle of the back of clevis 45 and extends outwardly perpendicular to its legs. This spring exerts a pull on bar 57 which pivots the clevis 45 around bolt 47 in a direction to tighten the band 51 around the cylindrical surface of the collar 42 and it also presses the band against the surface of the collar at 59 (Fig. 4). This spring is not sufficient to hold the band in tight frictional engagement with the surface of collar 42 but serves to hold the two clevises in a fixed relative position and the band under some tension. During a power stroke of the handle 39 the band is drawn up tightly around the collar but when the handle is swung back on a reset stroke the tension is released so that the band 51 may be slid around the surface of the collar 42 as the clevises are swiveled to a different position on the collar. The functions of the various portions of this unit will be more fully explained in connection with the operation of the device.

The handle 39 is preferably formed of a tubular member. The inner portion 62 of this handle is flattened as shown in Fig. 6, and, at the end of the handle a socket 63 is formed which extends downwardly perpendicular to the flat portion 62. The socket 63 is pivotally fitted over an upright post 65 which projects upwardly from a cross member 66 fastened between the braces 23 of one of the frames 12. The handle is connected to bar 57 of the friction unit by an arm 67, one end of which is pivotally connected to the handle at 68 and the other end of which is pivotally connected to the bar 57 at 69. During a power stroke of the handle, pull applied on the handle is transmitted to the unit 40 by arm 67 to tighten the band 51 so that it frictionally engages the collar 42. The socket 63 is easily disengaged from the post 65 and the handle and arm 67 are swung to a position close to the unit 40 when the frames 12 are folded in the manner shown in Fig. 7. In this view the handle and arm 67 are located behind the friction unit 40 and cannot be seen.

The operation of the ride is clearly brought out in Fig. 4. The preferred device is designed so that the handle 39 is pulled in a clockwise direction, as indicated, in order to make a power stroke which causes the frames 12 to rotate about upright 4. The reaction to this pulling force pivots the frames 12 in the counter-clockwise direction indicated. The handle swings in an arc around post 65 as the frames are rotated. The broken lines indicate the relative position of the handle and the frame when the frame has been rotated through an arc of about forty-five degrees from the position in which it is shown in solid lines.

The riders sit in the seats 36 facing one another and the handle is operated by the rider closest to the handle. On a power stroke the force applied to the handle is transmitted through the arm 67 to the bar 57 on the small clevis 45. Bar 57 exerts leverage on the small clevis 45 and

pivots the clevis forwardly about the bolt 47 thereby tightening the band 51 around the peripheral surface of the collar 42. The spring 56, as explained above, is not by itself strong enough to hold the band 51 in tight frictional engagement with the collar 42. The spring, however, does exert a sufficient amount of tension on the band to anchor the clevis 43 at a fixed position on the collar 42 until the additional leverage applied by the bar 57 pivots the small clevis 43 a sufficient amount to draw the band 51 tightly around the collar 42. As long as the leverage is applied by the arm 57 in this manner, the band 51 grips the collar 42 so tightly that clevis 43 cannot be turned around the collar. The result is that bar 57 is held in a stationary position and a component of the pulling force applied to the handle tends to swing the arm 67 in a counter-clockwise arc about the point 69. As the arm 67 is moved in this manner, it exerts a pull on the post 65 and consequently the frame is also rotated in a counter-clockwise direction.

As indicated in the drawings one end of the arm 67 is fastened to the lower portion of the flat surface of the handle. Therefore, when the handle has been swung to a position at the left of the rider operating it the arm 67 moves against the socket 63 and prevents the handle from being pivoted any further in the clockwise direction.

To reset the handle for another power stroke the rider pulls the handle in the reverse direction back to its original position. This movement of the handle releases the tension in the band 51 since the bar 57 can no longer maintain the necessary leverage on the clevis 43. As the handle is swung toward the rider's right side the arm 67 pushes against the arm 57. This relieves the tension in the band and the clevis 43 is swiveled around the collar 42 to a different angular position. The complete reset position of the handle will be at the dead-center point of the linkage which is a position of the linkage where the post 65, upright 4 and the pivot 69 are in a straight line. Preferably the arm 67 is curved to permit the handle to be completely reset to this dead-center position.

After the reset stroke is completed, a new power stroke is begun by rotating the handle in a clockwise direction and tension is applied to the band 51 to tighten it around the collar 42 in the same manner as was described above. At the end of each power stroke the handle is reset and another power stroke made. To summarize: On each power stroke the band 51 is tightened around the collar 42. On the reset stroke the tension in the band 51 is released and the clevis 43 is swiveled around the collar 42 to a different angular position where it remains until the power stroke is completed.

Once the frames have acquired sufficient momentum, very short power strokes may be used to maintain a desired speed. The handle need not be moved through its fullest arc to keep the frames rotating around the upright 4. The preferred linkage is designed so that a relatively small pulling force applied to the handle is sufficient to rotate the frames.

The ride may be designed so that the handle rotates the frames in the reverse direction to that shown. The ride is not limited to use with the particular type of friction unit shown. It is also evident that were the clevises of different sizes and, for example, the distances between the bolts

47 and 55 were changed, a slightly different movement of the parts would be accomplished. The ride may be designed with more than two frames 12. Other modifications may be made within the scope of the claims.

What I claim is:

1. A collapsible merry-go-round ride which comprises a cylindrical upright, upper and lower collars rotatable about the upright, the lower collar being slidable on the upright, a flat bearing surface adjacent the base of the upright from which the upright rises perpendicularly and on which the lower collar is rotatable in its lowermost position, a plurality of frames relatively heavy to withstand compression pivotally mounted on the lower collar, a seat on each frame, and a plurality of light tension braces, each frame being pivotally connected to one end of one of said braces at a distance from said pivotal mounting on the collar which distance is greater than the length of the brace, the other end of each brace being pivotally connected to the upper collar, whereby the frames may be swung upright by sliding the lower collar away from the bearing surface.

2. The ride of claim 1 in which there are two frames with legs straddling the lower collar, means on each side of the lower collar pivotally fastening both legs to the collar, and removably attached to the upright below the bearing surface legs which extend outwardly from the upright substantially as far as the outer ends of the frames when the lower collar is resting on the bearing surface.

3. A collapsible merry-go-round ride which comprises a cylindrical upright, upper and lower collars rotatable about the upright, the lower collar being slidable on the upright, a flat bearing surface from which the upright rises perpendicularly and on which the lower collar is rotatable in its lowermost position, a plurality of frames pivotally mounted on the lower collar, a seat on each frame, and a plurality of braces, each frame being pivotally connected to one end of one of said braces at a distance from said pivotal mounting on the collar which distance is greater than the length of the brace, the other end of each brace being pivotally connected to the upper collar, whereby the frames may be swung upright by sliding the lower collar away from the bearing surface, a handle pivotally mounted on one of the braces and contractible frictional gripping means about the upright with the handle connected thereto and adapted to contract the gripping means to grip means on the upright whereby the handle is used to rotate the frames about the upright.
